US0D1020811S

(12) **United States Design Patent** (10) Patent No.: **US D1,020,811 S**
(45) Date of Patent: ** Apr. 2, 2024

(54) **EXCAVATOR**

(71) Applicant: **SANY MARINE HEAVY INDUSTRY CO., LTD.**, Zhuhai (CN)

(72) Inventor: **Jiaxiong Li**, Guangdong (CN)

(**) Term: **15 Years**

(21) Appl. No.: **35/516,143**

(22) Filed: **Aug. 30, 2022**

(80) **Hague Agreement Data**

Int. Filing Date: **Aug. 30, 2022**

Int. Reg. No.: **DM/226304**

Int. Reg. Date: **Aug. 30, 2022**

Int. Reg. Pub. Date: **Feb. 3, 2023**

(51) LOC (14) Cl. **15-03**
